CLAIM

The ornamental design for a floorstand display unit, as shown and described.

DESCRIPTION

FIG. 1 shows a perspective view of my design for a floorstand display unit;

FIG. 2 shows a front elevational view thereof;

FIG. 3 shows a rear elevational view thereof;

FIG. 4 shows left side elevational view thereof;

FIG. 5 shows a right side elevational view thereof;

FIG. 6 shows a top view thereof;

FIG. 7 shows a bottom view thereof; and,

FIG. 8 shows a partially exploded perspective view thereof.

The elements shown in broken lines depict environmental structure only and form no part of the claimed design.
